UNITED STATES PATENT OFFICE.

PAUL SCHUYLER VAN BLOEM, OF HEMPSTEAD, NEW YORK, ASSIGNOR TO VIKING PRODUCTS CORPORATION, OF NEW YORK, N. Y., A CORPORATION OF NEW YORK.

ELEVATOR SIGNAL.

Application filed October 8, 1925. Serial No. 61,242.

To all whom it may concern:

Be it known that I, PAUL SCHUYLER VAN BLOEM, a citizen of the United States, and resident of Hempstead, in the county of 5 Nassau and State of New York, have invented certain new and useful Improvements in Elevator Signals, of which the following is a specification.

This invention relates to signals for indicating the approach of an elevator car and the direction of its travel.

An object of the invention is to provide an elevator signal of simple form which when unilluminated will be inconspicuous 15 but which when illuminated, upon the approach of an elevator car, will be rendered very conspicuous and will distinctly indicate the direction of travel of the car.

A further object is the provision of a signal lens in the form of a cover adapted to substantially conceal a lamp. The lamp cover is placed over a signal lamp projecting from or mounted in the wall adjacent the elevator shaft and adapted to be illuminated when the elevator car approaches. The cover bears a direction indicating character which when unilluminated by the lamp is indistinct or entirely invisible but which when the lamp is illuminated by the approach of a car will become distinctly visible. The cover lens is also designed to reflect light rays received from the signal lamp and direct them outwardly and rearwardly upon the wall back of the signal in a manner to cause the signal to be surrounded with a halo of light. This increases the conspicuity of the signal and calls attention to the approach of the car. Other light rays received by the cover lens are directed outwardly and forwardly in a manner to render the lens brilliantly luminous and give it a highly distinctive and ornamental appearance.

In the drawings:

Fig. 1 is a front view of the signal lens; Fig. 2 a sectional view showing the lens mounted over the signal lamp; and

Fig. 3 a vertical transverse section through the lens taken on the line 3—3 of Fig. 2.

Referring to the parts by numerals, 1 represents the signal lamp which is so mounted as to be located in a proper relation to the signal lens, either in or upon a wall 2 adjacent an elevator shaft. The lamp 1 is normally unilluminated, but upon the ap-

proach of an elevator car it is adapted to be illuminated by the closing of a circuit (not shown).

A dished or substantially cup-shaped glass lens 3 is placed over the lamp 1 and surrounds and encloses the outwardly projecting end of the lamp. The lens 3 is formed with a convex, substantially vertical, front signal-bearing portion or wall 4, preferably circular in outline. The front signal-bearing portion is supported by an integral, continuous, rearwardly extending, annular portion or member 5. The forward end of the supporting portion is connected to the front signal-bearing portion around its edges and the rear end of said supporting portion is adapted to be fitted against the supporting wall or other lens supporting medium and to be secured thereto in any suitable manner. In the present instance the lens is supported by an annulus 6 which is secured to the wall 2 by screws 7. The enclosing wall or member is preferably continuous and annular as shown in Figs. 1 and 2. The said supporting portion may, however, be formed with a different contour. The enclosing member preferably diverges or enlarges rearwardly and is of material depth in order to off-set the signal-bearing member from the supporting wall and to completely enclose the projecting portion of the signal lamp 1.

The outer face 8 of the signal-bearing front wall or portion 4 of the lens is made with a smooth finish and the inner face of said wall is formed with a depression 9 in the form of a direction indicating character. The rear surface of the front portion 4, surrounding the depression 9 is embossed or formed with small light-diffusing protuberances 10. The character depression is of material depth and all of its walls are smooth. The side walls 11 of the depression are disposed substantially at right angles to the bottom 12 of the depression whereby they will reflect light rays from the lamp and direct them outwardly through the bottom. When the lamp is illuminated by the approach of a car the entire front face of the lens will become luminous. The direction indicating character will be rendered more luminous than its surrounding field owing to the reduced thickness of the front wall at the bottom of the depression and owing to the fact that the bottom of the depression is smooth and permits the light to pass directly

through it, while the embossed surface 10 of the surrounding field will diffuse the light received from the lamp. The reflecting side walls 11 of the depression also causes a concentration of light rays upon the character. The decided contrast in luminosity between the character and the surrounding field will therefore cause the character to be clearly outlined.

10 The annular outer surface of the portion 5 has a series of annular light-reflecting ribs 13 formed thereon. These ribs extend circumferentially entirely around the portion 5, and are arranged side by side from front to 15 back and extend in planes parallel to the wall 2 when the lens is mounted in position over the lamp, as shown in Fig. 2, of the drawings. Each rib 13 tapers outwardly slightly in cross section and is formed with 20 a continuous forwardly facing reflecting surface 14, a continuous rearwardly facing reflecting surface 15 and a continuous top surface 16 flat in cross section. The reflecting surface 14 is disposed at such an angle that most of the light rays from the lamp passing through the thickness of the portion 5 and received by said surface will fall thereon at an angle of incidence greater than the critical angle, or the angle at which they 25 would emerge through the surface. There is therefore a total reflection of these light rays within the rib and they are directed outwardly and rearwardly through the rib and emerge through the flat top surface 16 of the rib. This top surface will refract the emerging rays and direct them still further toward the rear. This causes a halo of light 30 to be projected upon the wall or lens support back of the lens. This halo surrounds 35 the signal and greatly increases its conspicu- 40 ness and calls attention to the approach of a car. The rear reflecting surfaces 15 of the ribs also serve to reflect the rays received from the lamp in a manner similar to the 45 reflecting action of the forward faces 14. In the case of the faces 15, however, the rays are reflected outwardly and forwardly through the ribs, emerge through the top 50 surfaces 16 and are refracted forwardly toward the observer. This concentration and 55 direction of the rays will give the ribs 13 the appearance of brilliantly luminous rings surrounding the signal, and add to the beauty and effectiveness of the signal.

60 The ribs 13 are spaced apart along the outer surface of the lamp surrounding portion 5 and thus leave continuous surfaces 17 exposed between the ribs. These surfaces 17 are smooth and substantially parallel in cross section with the inner surface of the lamp-surrounding portion. Light rays from the lamp may therefore pass directly out through said surfaces without reflection or refraction and render them luminous when 65 viewed from the side. When laterally

viewed the surfaces will therefore appear as spaced, brilliantly luminous bands. The flat top surfaces 16 of the ribs 13 are also substantially parallel to the inner surface of the portion 5 and will therefore permit rays 70 from the lamp to pass through them in the same manner as in the case of the surfaces 17. These surfaces 16 will also appear as luminous bands when viewed from the side. These latter bands will be greater in diameter than the bands defined by the surfaces 17 and will be separated therefrom by the tapering sides of the ribs. The tapering sides appear in shadow when viewed from the side owing to the fact that they direct 80 the light rays forwardly and backwardly. The lens will therefore present a distinctive ornamental appearance when viewed from any direction.

85 The inner surface of the lamp-surrounding portion 5 is formed with a continuous series of small light diffusing ribs 18. These ribs extend longitudinally throughout substantially the length of the portion 5 and are prismatic in cross section. The function of ribs 18 is to diffuse the rays from the lamp around the lens and conceal the enclosed lamp. Owing to the longitudinal arrangement of the ribs and their prismatic form, the diffusion will be entirely lateral 90 with relation to the axis of the lens. There will be no diffusion toward the front or back of the lens and consequently no diminution in the number of rays passing laterally out through the lamp-surrounding portion. By 95 arranging for the light diffusion within the lens, the outer surfaces of the lamp-surrounding portion may all be made smooth so that they will cause the brilliant luminous effect just described.

100 What I claim is:

1. A device of the class set forth comprising a substantially cup-shaped glass covering for a wall lamp, formed with a vertically arranged front portion bearing a direction-indicating character; an annular lamp-surrounding portion extending rearwardly from said front portion substantially horizontally and having its front end closed by the front portion and its rear end open and adapted to abut the wall; reflecting surfaces carried by and arranged around said lamp-surrounding portion, said surfaces being disposed transversely with reference to the axis of the lamp-surrounding portion and adapted to receive light-rays 110 from the enclosed lamp and reflect them outwardly and rearwardly to create a halo of light surrounding the lamp covering upon the wall back of the covering; and a light-diffusing surface extending around the inner side of the lamp-surrounding portion and adapted to diffuse light rays from the lamp laterally only with relation to the axis of 115 the lamp-surrounding portion.

2. A device of the class set forth comprising a substantially cup-shaped glass covering for a wall lamp, formed with a vertically arranged front portion bearing a direction-indicating character; an annular lamp-surrounding portion extending rearwardly from said front portion substantially horizontally and having its front end closed by the front portion and its rear end open and adapted to abut the wall; reflecting surfaces carried by and arranged around said lamp-surrounding portion, said surfaces being disposed transversely with reference to the axis of the lamp-surrounding portion and adapted to receive light-rays from the enclosed lamp and reflect them outwardly and rearwardly to create a halo of light surrounding the lamp upon the wall back of the covering; and light-diffusing ribs extending longitudinally fore-and-aft of the lamp-surrounding portion and arranged in a continuous series upon and around the inner surface thereof.
3. A device of the class set forth comprising a substantially cup-shaped glass covering for a wall lamp, formed with a vertically arranged front portion bearing a direction-indicating character; an annular lamp-surrounding portion extending rearwardly from said front portion substantially horizontally and having its front end closed by the front portion and its rear end open and adapted to abut the wall, reflecting surfaces carried by and arranged around said lamp-surrounding portion, said surfaces being disposed transversely with reference to the axis of the lamp-surrounding portion and adapted to receive light rays from the enclosed lamp and reflect them outwardly and rearwardly to create a halo of light surrounding the lamp covering upon the wall back of the covering, and a light-diffusing surface extending around the inner side of the lamp-surrounding portion and adapted to diffuse light rays from the lamp laterally only with relation to the axis of the lamp-surrounding portion.
4. A device of the class set forth comprising a substantially cup-shaped glass covering for a wall lamp, formed with a vertically arranged front portion bearing a direction-indicating character; an annular lamp-surrounding portion extending rearwardly from said front portion substantially horizontally and having its front end closed by the front portion and its rear end open and adapted to abut the wall; rearwardly reflecting surfaces carried by and arranged around said lamp-surrounding portion, said surfaces being disposed transversely with reference to the axis of the lamp-surrounding portion and adapted to receive rays from the enclosed lamp and reflect them outwardly and rearwardly toward the wall back of the lamp covering to surround the covering with a halo of light; forwardly reflecting surfaces carried by and arranged around the lamp-surrounding portion, said forwardly reflecting surfaces being disposed transversely with relation to the axis of the lamp-surrounding portion, and adapted to receive rays from the lamp and reflect them outwardly and forwardly to render the lamp-surrounding portion luminous, and light-diffusing ribs extending longitudinally fore-and-aft of the lamp-surrounding portion and arranged in a continuous series upon and around the inner surface thereof.
5. A device of the class set forth comprising a substantially cup-shaped glass covering for a wall lamp, formed with a front portion bearing an indicating character; a body or lamp-surrounding portion open at its rear end and closed at its front end by the said front portion, a plurality of ribs formed on and extending peripherally around the outer surface of the said body, said ribs being spaced apart fore-and-aft of the body and each being formed with a front reflecting surface and a rear reflecting surface, whereby light rays received from the lamp through the lamp-surrounding portion will be reflected by the forward surfaces of the ribs and directed outwardly and rearwardly toward the room wall back of the lamp covering to surround the covering with a halo of light and whereby other light rays will be reflected and directed outwardly and forwardly by the rear surfaces of said ribs; and light-diffusing ribs extending longitudinally fore-and-aft of the lamp-surrounding portion and arranged in a series upon and around the inner surface thereof.
6. A device of the class set forth comprising a substantially cup-shaped glass covering for a wall lamp formed with a front portion bearing an indicating character; a body or lamp-surrounding portion open at its rear end and closed at its front end by the said front portion; means formed on the outer surface of the said body adapted to receive light rays from the lamp and reflect and refract them outwardly and rearwardly toward the room wall back of the lamp covering to surround the covering with a halo of light; and light-diffusing ribs extending longitudinally fore-and-aft of the lamp covering and arranged in a series upon and around the inner surface of the lamp-surrounding portion.
7. A device of the class set forth comprising a substantially cup-shaped glass covering for a wall lamp formed with a front portion having a depression in its rear face in the form of an indicating character, the portion of said rear face surrounding the character depression being formed to diffuse light; and a lamp-surrounding portion open at its rear end and closed at its front end by said front portion and formed to direct rays

received from the enclosed lamp outwardly and rearwardly toward the room wall back of the covering to surround the covering with a halo of light.

- 5 8. A device of the class set forth comprising a substantially cup-shaped glass covering for a wall lamp, formed with a front portion bearing a direction indicating character; an annular body or lamp-surrounding portion open at its rear end and closed at its front end by said front portion; a plurality of annular parallel ribs formed on and extending around the outer peripheral surface of said body portion, said ribs being spaced apart fore-and-aft of the body portion and each rib being formed with a continuous front reflecting surface, a continuous rear reflecting surface and an annular top or outer surface straight in fore-and-aft section, whereby light rays received from the lamp through the lamp surrounding portion will be reflected outwardly and rearwardly by the front surfaces of the ribs and will be caused to be rearwardly refracted toward the room wall by said outer surfaces of the ribs to surround the covering with a halo of light, and other rays will be reflected outwardly and forwardly by the rear surfaces of the ribs and will be caused to be forwardly refracted by the said outer surfaces thereof; and light-diffusing ribs extending longitudinally fore-and-aft of the lamp-surrounding portion substantially the depth thereof and arranged in a continuous series upon and around the inner surface of said portion, the outer surface of the lamp-surrounding portion being formed with a plurality of annular surfaces straight in fore-and-aft section between the bases of said ribs.

- 40 9. A device of the class set forth comprising a substantially cup-shaped glass covering for a wall lamp formed with a front portion; a body or lamp-surrounding portion closed at its front end by the said front portion; means formed on the outer surface of the said body adapted to receive light rays from the lamp and reflect them outwardly and rearwardly toward the room wall back of the lamp covering to create a halo of light around the covering; and light-diffusing ribs extending longitudinally fore-and-aft of the lamp covering and arranged in a series upon and around the in-

ner surface of the lamp-surrounding portion.

10. A device of the class set forth comprising a substantially cup-shaped glass covering for a wall lamp formed with a front portion; a body or lamp-surrounding portion closed at its front end by the said front portion; means formed on the outer surface of the said body adapted to receive light rays from the lamp and reflect them outwardly and rearwardly toward the room wall back of the lamp covering to create a halo of light around the covering; and a light-diffusing surface extending around the inner side of the lamp-surrounding portion and adapted to diffuse light rays laterally only with relation to the axis of the lamp-surrounding portion.

11. A device of the class set forth comprising a substantially cup-shaped glass covering for a wall lamp formed with a front portion, a body or lamp-surrounding portion extending rearwardly from said front portion and having its front end closed by the front portion and its rear end adapted to abut the wall; light-reflecting surfaces arranged upon and around the outer lamp-surrounding surface of the body, said surfaces being disposed transversely with reference to the axis of the body and adapted to receive light rays from the enclosed lamp and reflect them outwardly and rearwardly to create a halo of light around the lamp covering upon the wall back of the covering; and a light-diffusing surface extending around the inner side of the lamp-surrounding portions.

12. A device of the class set forth comprising a substantially cup-shaped glass covering for a wall lamp formed with a front portion; a lamp-surrounding portion closed at its front end by said front portion and formed with inner and outer lamp-surrounding surfaces; means carried by one of said lamp-surrounding surfaces adapted to receive light rays from the enclosed lamp and reflect them outwardly and rearwardly toward the room wall back of the covering to create a halo of light around the covering, the other of said lamp-surrounding surfaces being formed to diffuse light rays.

In testimony whereof I hereunto affix my signature.

PAUL SCHUYLER VAN BLOEM.
